UNITED STATES PATENT OFFICE.

HARRY D. MADDEN, OF BLOOMFIELD, NEW JERSEY, ASSIGNOR TO WESTINGHOUSE
LAMP COMPANY, A CORPORATION OF PENNSYLVANIA.

GLASS-CUTTING MACHINE.

1,123,336.

Specification of Letters Patent.

Patented Jan. 5, 1915.

Application filed December 5, 1910. Serial No. 595,634.

To all whom it may concern:

Be it known that I, HARRY D. MADDEN, a citizen of the United States, and a resident of Bloomfield, in the county of Essex and State of New Jersey, have invented a new and useful Improvement in Glass-Cutting Machines, of which the following is a specification.

My invention relates to glass cutting machines, and it has for its object to provide a simple machine of large capacity for accurately cutting rods or canes of glass into comparatively short lengths.

Figure 1 of the accompanying drawings is a view, in section and in elevation, of a machine constructed in accordance with my invention, and Fig. 2 is a plan view of the said machine.

The machine comprises a hollow base 1 and a superposed standard consisting of vertical rods 2 and spaced horizontal plates 3 and 4 that are carried by the rods and are provided with alined apertures 5 arranged in circles.

Extending between the plates 3 and 4 and connecting the apertures therein, are vertical tubes 6, which, together with the apertured plates, constitute guides through which are fed the rods or canes 7 to be cut into lengths.

The plate 4 and the base 1 are provided with lateral bearings 8 and 9, respectively, for a vertical shaft 10 upon the lower end of which is loosely mounted a main driving pulley 11 that is adapted to be driven by a belt (not shown) from any suitable source of power, and the upper face of the hub 12 of which is provided with bosses and recesses constituting a clutch member 13. Directly above the pulley 11, a corresponding clutch member 14 is secured to, but is longitudinally movable on, the shaft 10, and is adapted to be moved into and out of engagement with the clutch member 13, to provide or to interrupt an operative connection between the pulley 11 and the shaft 10, by means of a lever 15, one end of which projects through a slot in the base 1 and is provided with a thumb nut 16 for clamping the lever in either clutch-engaging or clutch-disengaging position.

Mounted upon the shaft 10, directly beneath the plate 4, is an eccentric 19 having a rubber or other suitable resilient edge or

tire 20, the portion of which that is most remote from the shaft being adapted to engage the rods or canes 7 and to successively clamp them stationarily.

A short distance beneath the eccentric 19, the shaft 10 also carries an arm or plate 22 upon the upper face of which a member 23, having a slotted outer end, is pivotally mounted, a hardened steel or other suitable cutter 24 being rotatably mounted in the slot at the outer end of the said member. The member 23 is normally retained in the position shown in Fig. 2 by means of a helical compression spring 25 that is interposed between the said member and a shoulder upon a screw 26 that is threaded in a boss on the arm 22 and is provided for the purpose of adjusting the pressure exerted by the spring 25. The normal position of the member 23 is adjustable and is determined by means of another screw 27 that is threaded in another boss carried by the arm 22. The said parts provide a resilient mounting for the revolvable cutter that is capable of a limited degree of movement, independently of its revolution. Engaging the rods 7, upon their outer faces, directly opposite the points where they are engaged and cut by the cutter 24, is a stationary ring 28 having a V-shaped inner edge, which forms a narrow support against which the rods are pressed by the cutter.

Secured to one side of, and carried by the arm 22, and comprising nearly one complete convolution, is a helical slide or chute 29 upon which the rods or canes drop when released by the member 20 and by means of which they are lowered, during the rotation of the slide, upon a rest or plate 30 that is carried by, and is longitudinally adjustable on, the shaft 10 to determine the length of the pieces into which the rods or canes are to be cut. The rods or canes are thus lowered upon the rest 30 without undue jar, and breakage is thereby reduced to a minimum.

Mounted upon the shaft 10, beneath the arm 22, is a second eccentric 31 that is provided with a rubber or other suitable resilient tire 32, the portion of which most remote from the shaft is adapted to engage the rods or canes 7 at about the time they are engaged by the cutter 24 or immediately thereafter and to press their lower ends out.

wardly, in order to deflect the same and cause breakage thereof at the points where they have been cut.

In the operation of the machine, the rods 5 are fed into the apertures in the plate 3 and lowered upon the helical chute 29, and the plate 30, the greater number of them resting upon the chute, while only a few that are between the lower end of the chute and the 10 cutter 24, rest upon the plate 30. As the shaft 10 is rotated, the member 20 engages the rods or canes 7 slightly in advance of the cutter 24 and presses the same against the sides of the apertures in the member 4 and 15 against the inner face of the ring 28. They are thus prevented from vibrating when the cutter engages them. When the cutter 24 engages the rods, it scratches or cuts them, and, by reason of its resilient mounting, the 20 cutting operation is performed effectively and with a minimum breakage of the rods or canes.

At the same time that the rods are cut, or a short interval thereafter, the member 25 32 engages the lower ends of the rods and deflects them outwardly, thereby causing breakage at the points where they were scratched or cut. The member 20 continues to engage the rods or canes and prevents 30 them from dropping for a short interval after the rods have been cut and broken and until the slide or chute 29 has been brought beneath the newly cut ends thereof. After the rods have dropped upon the slide or 35 chute, they are gradually lowered by the revolution of the slide until they drop upon the rest 30, by means of which the length into which the rods are to be cut is determined, the rods being cut only when standing upon the rest.

I claim as my invention:

1. A rod cutting machine comprising a plurality of vertical guides for the rods, means for successively clamping and releasing the rods in the guides, a cutter that successively engages the rods, a rest for the rods, and a movable inclined slide for lowering the rods from the guides upon the rest.

2. A rod cutting machine comprising a plurality of guides arranged in a circle, a 50 rotatable eccentric for successively clamping and releasing the rods, a revoluble cutter, a rotatable eccentric for breaking the rods after having been cut, a rest for the rods, and a rotatable helical slide for lowering the 55 rods upon the rest.

3. A rod cutting machine comprising a plurality of guides arranged in a circle, a 60 rotatable eccentric for successively clamping and releasing the rods, a revoluble cutter, a 65 ring engaging the rods upon the sides opposite the points of cutting, a rotatable eccentric for breaking the rods after having been cut, a rest for the rods, and a rotatable helical slide for lowering the rods upon the 70 rest.

4. A rod cutting machine comprising a plurality of guides for the rods, means for successively clamping and releasing the rods, a revoluble resiliently mounted cutter, 75 a ring adapted to engage the rods upon the sides opposite the points of cutting, means for breaking the rods after having been cut, a rest for the rods, and means for gradually lowering the rods upon the 80 rest.

5. A rod cutting machine comprising a plurality of guides arranged in a circle, and a cutter rotating about the center of said circle and adapted to successively engage the 85 rods upon their inner faces.

6. A rod cutting machine comprising a plurality of vertical guides arranged in a circle, a revoluble cutter adapted to successively engage the rods upon their inner faces, a rest for the rods beneath the cutter, and means for gradually lowering the rods 90 upon the rest.

In testimony whereof, I have hereunto subscribed my name this 23rd day of November, 1910.

HARRY D. MADDEN.
